CLAIM

The ornamental design for a directional downspout connector, as shown and described.

DESCRIPTION

1. Directional downspout connector

1.1 is a perspective view of the design for a directional downspout connector;

1.2 is a right side view thereof;

1.3 is a left side view thereof;

1.4 is a top view thereof;

1.5 is a bottom view thereof;

1.6 is a front view thereof;

1.7 is a back view thereof;

1.8 is an exploded perspective view thereof;

1.9 is a perspective view thereof in a first articulated position;

1.10 is a perspective view thereof in a second articulated position;

1.11 is a perspective view thereof shown in use in its environment; the broken lines illustrate the environment and form no part of the claimed design.

The broken lines in reproduction 1.11 are for the purpose of illustrating environmental structure and form no part of the claimed design. All other broken lines are for the purpose of illustrating portions of the directional downspout connector that form no part of the claimed design.

1 Claim, 11 Drawing Sheets
